UNITED STATES PATENT OFFICE.

AUGUSTINE CROSSON, OF MOUNDS, ILLINOIS.

PEN AND PENCIL HOLDER.

1,281,299.

Specification of Letters Patent. Patented Oct. 15, 1918.

Application filed September 25, 1917. Serial No. 193,144.

To all whom it may concern:

Be it known that I, AUGUSTINE CROSSON, a citizen of the United States, residing at Mounds, in the county of Pulaski and State 5 of Illinois, have invented certain new and useful Improvements in Pen and Pencil Holders, of which the following is a specification.

This invention relates to devices for supporting small articles such as fountain and other pens, pencils and the like and adapted to be connected to a belt or like support and readily attached and detached or moved to any point upon the belt.

15 With these and other objects in view, the invention consists in certain novel features of construction, as hereinafter shown and described and then specifically pointed out in the claim; and in the drawings illustrative of the preferred embodiment of the invention—

Figure 1 is a perspective view of the improved device disconnected from any support;

25 Fig. 2 is a perspective view on a reduced scale of a conventional belt with the device applied;

Fig. 3 is a sectional detail illustrating the manner of connecting the holding strap to 30 the sheath.

Corresponding and like parts are referred to in the following description and indicated in all the views of the drawings by the same reference characters.

35 The improved device includes a sheath or holder and may be of any suitable form and employed for holding fountain and other pens, pencils and the like, but it is not desired to limit the invention to any specific 40 form of the body of the holder or sheath. The body of the holder is represented conventionally at 10 and includes an upwardly directed flap portion 11. The holder employed for illustrating the application of 45 the invention comprises a back portion of a plurality of thicknesses of material, such as leather, and one or more pockets or receptacles attached to the back as shown. Formed through the flap 11 is a transverse 50 slot 12 located some distance below the up-

per end of the flap and adapted to receive a supporting strap which is folded near one end as shown at 13, and passed by the folded portion through the slot 12. By this means the strap comprises two portions, a relatively short portion 14 and a longer portion 15. The shorter portion 14 is riveted or otherwise secured to the flap 11 above the slot 12 by a rivet or like device 16. By this means the strap is firmly connected to the flap 11 of the sheath or holder leaving a relatively large part of the portion 14 of the strap extending above the upper end of the flap. The terminals of the portions 14—15 of the strap are designed to be coupled together, for instance by a glove fastener indicated at 17—18. The longer portion 15 of the strap is designed to be folded over a belt, represented at 19, and when the snap devices 17—18 are closed the sheath or 70 holder will be firmly coupled to the belt while at the same time readily slideable thereon so that the wearer can quickly and easily adjust the position of the holder or sheath upon the belt.

75 The strap will be of a length preferably to closely engage the belt with the upper end of the flap relatively close to the lower edge of the belt, as shown in Fig. 3, while the folded over part of the portion 15 of the belt will closely engage the upper edge of the belt. By this means the sheath or holder is held from vertical movement relatively to the belt, while at the same time free to be moved longitudinally thereof 80 when required.

The improved device is simple in construction, can be inexpensively manufactured and applied without material structural change to sheaths or holders of various 90 forms and constructed of various materials.

Having thus described the invention, what is claimed as new is:

A device of the class described comprising a body adapted to support articles and having a slot spaced from one end, a strap passing through the slot and folded near one end against the opposite faces of the body and with portions of unequal length extending in advance of the body and co- 95 100

acting with the adjacent end of the body to form a seat adapted to receive the lower part of a belt, a fastening device operating through the folded portions of the strap and the material of the body therebetween to rigidly connect the strap to the body,

and means for detachably coupling the longer portion to the shorter portion of the strap and adapted to inclose the upper portion of the belt.

In testimony whereof I affix my signature.

AUGUSTINE CROSSON. [L.S.]
